UNITED STATES PATENT OFFICE.

GEORGE E. W. BROWN, OF RUSHVILLE, INDIANA.

ATTACHMENT FOR WORKBENCHES.

Application filed March 19, 1926. Serial No. 95,953.

The present invention relates to an attachment for a work bench in the wood working art or the like, and has for its principal object to provide a structure which will function broadly as a work holder in an efficient and reliable manner.

Another important object of the invention is to provide an attachment of this nature which will hold work for various operations such as planing or the like, the work being held horizontally on the bench or vertically thereof.

Another very important object of the invention is to provide a structure of this nature which is easily adjusted for different sizes and one which is strong and durable, yet simple in its construction.

With the above and numerous other objects in view as will appear as the description proceeds, the invention resides in certain novel features of construction, and in the combination and arrangement of parts as will be hereinafter more fully described and claimed.

25 In the drawing:—

Figure 1 is a top plan view of the attachment showing the same on one corner of a work bench,

Fig. 2 is an enlarged transverse section therethrough, taken substantially on the line 2—2 of Fig. 1, and

Fig. 3 is an end elevation thereof,

Fig. 4 is a side elevation thereof,

Fig. 5 is an enlarged fragmentary longitudinal section therethrough, taken substantially on the line 5—5 of Fig. 1, and

Fig. 6 is an enlarged detail section taken substantially on the line 6—6 of Fig. 1.

Referring to the drawing in detail, it will be seen that letter A denotes the top of a work bench. The number 5 denotes the platform or body of my attachment, from which extends a pair of arms 6 adapted to be fixed to the under surface of the work bench A so that the platform 5 is flush with the upper surface thereof. The attachment is preferably located in one corner of the bench A so that one longitudinal edge of the platform 5 is contiguous with the one edge of the work bench while one edge of the platform is in alinement with another edge of the work bench as is clearly illustrated in Fig. 1.

55 A pair of arms 7 project forwardly from the outer longitudinal edge of the platform 5. A pair of rectangular frames 8 depend

from the arms 7 and are braced in respect to each other at their lower ends by a bar 9. Screws 10 or like peg elements project from the frames 8. A pair of bars 11 are provided with longitudinally extending slots 12 adjacent their upper ends for receiving the screws 10. One longitudinal edge of each slot 12 is provided with a plurality of notches 13 for receiving the screws 10 so that the bars 11 may be raised or lowered to different positions.

A worm shaft 14 extends through the frames 8 and are journaled through the bars 11. An elongated stationary jaw 15 is disposed adjacent one arm 7 and is supported by the worm shaft 14, the latter being journaled therethrough as is clearly illustrated in Fig. 6. The worm shaft is threaded through a nut 16 fixed to a movable jaw 17 through which the shaft also extends. A polished rod 18 extends longitudinally of the platform 5 being fixed to the upper ends of the frames 8 by welding or in any other suitable manner.

80 The jaws 15 and 17 are vertically disposed, and slidably engage the polish rod 18 and the bar 9. As is illustrated to advantage in Fig. 2, the upper end of each jaw is reduced and terminates in a gripping portion 19 which is preferably serrated or otherwise scored to provide a roughened surface. A crank 20 is fixed on one end of the worm shaft 14 so that rotary motion may be imparted thereto for sliding the movable jaw 17 toward or away from the fixed jaw 15.

It will thus be seen that a piece of work may be clamped between these jaws 15 and 17 to rest on the platform 5 and work bench A. It is also to be noted that the bars 11 may be raised or lowered, thereby raising or lowering the parts supporting thereon such as the shaft 14 and the jaws 15 and 17. This allows an adjustment so that the work may be clamped in such a manner that the jaws 15 and 17 will not protrude upwardly beyond the upper surface of said work.

85 A sheave 22 extends longitudinally under the platform 5 and is secured thereto in any suitable manner. A lug 23 projects from an intermediate portion of the sheath 22. A shank 24 is slidable in the sheath 22, and terminates in a head 25 which crosses the end of the shank to provide a clamping jaw 26 and a bearing extension 27. A screw 105 shaft 28 is journaled through the bearing extension 27 and is threaded through the lug

23. Crank 29 is fixed on the outer end of the threaded shaft 28.

It will thus be seen that by turning crank 29 the clamp jaw 26 may be moved toward or 5 away from the end of the platform 5. Thus a door, or any other work, may be clamped in a vertical position on the end of the platform for planing or other purposes.

A recess 30 is provided in the platform 5 10 and a sheath 31 depends from the bottom of the platform in registry with an opening leading into the recess 30. The sheath 31 slidably receives a shank 32 having a stop head 33 on the upper end thereof seatable 15 in the recess 30. This stop head on one longitudinal edge is preferably provided with teeth 34. A set screw 35 is threaded 20 transversely through the sheath 31 so that the stop head 33 may be raised or lowered and held in different adjusted positions in 25 relation to the upper surface of the platform 5. This stop head is used so that a board resting on the work bench may have one end in engagement therewith, and the head may be positioned below the upper surface 30 of the board in order that said board may be planed.

The stop, of course, may be used in other 35 obvious manners. I have described the details of this invention in each instance with an example of the utility thereof, but it is quite obvious that the parts are capable of

many usages not detailed herein. The present embodiment of the invention has been disclosed merely by way of example, since 35 in actual practice it has proven to be compact and convenient, and to attain the other features of advantage enumerated as desirable in the statement of the invention and the 40 above description.

It is apparent, however, that numerous changes in the details of construction, and in the combination and arrangement of parts 45 may be resorted to without departing from the scope or spirit of the invention as hereinafter claimed, or sacrificing any of its advantages.

Having thus described my invention, what I claim as new is:—

A device of the class described including 50 in combination, a platform, means for mounting the platform on a work bench so that the upper surface of the platform is flush with the upper surface of the work bench, clamping means mounted on one side 55 of the platform, a mechanism for mounting the second means so that said means may be adjusted vertically, a movable clamp associated with one end of the platform, said platform provided with a recess, a stop head seatable in said recess, and means for raising and lowering the stop head.

In testimony whereof I affix my signature.
GEORGE E. W. BROWN.
